UNITED STATES PATENT OFFICE.

ANDREAS P. LUNDIN, OF NEW YORK, N. Y., ASSIGNOR TO WELIN DAVIT AND LANE & DE GROOT COMPANY, CONSOLIDATED, A CORPORATION OF NEW YORK.

CRANE OR DERRICK.

986,399.

Specification of Letters Patent. Patented Mar. 7, 1911.

Application filed October 1, 1908. Serial No. 455,746.

To all whom it may concern:

Be it known that I, ANDREAS P. LUNDIN, a citizen of the United States, and a resident of the borough of Manhattan, city, county, and State of New York, have invented certain new and useful Improvements in Cranes or Derricks, of which the following is a specification.

My invention relates to improvements in cranes or derricks which perform the operations of lifting and hoisting the load to be moved, and swinging the same around horizontally to the place desired. It may be utilized in either land or marine work for the handling of cargoes of ships or any other loads.

In the accompanying drawings, in which similar reference characters designate corresponding parts, I have illustrated preferred embodiments of my invention, Figures 1, 2 and 3 illustrating a construction adapted for comparatively light work, and Figs. 4 and 5, showing a construction particularly adapted for the handling of heavy loads. In these drawings only manual means for the operation of such devices are illustrated, but it is obvious that the same may be operated by electric, steam or other suitable power.

Referring to the drawings, Fig. 1 is a side elevation of my improved crane mounted on a cylindrical pedestal or mast, Fig. 2 is a rear view thereof; Fig. 3 is a detail view of the clutching mechanism and connecting parts shown in Figs. 1 and 2; Fig. 4 is a side view, partially in section of a crane or derrick embodying my invention; and Fig. 5 is a transverse section on the line 5—5 of Fig. 4, looking downwardly, the crane arm and part of the frame being omitted for the purpose of showing the other parts more clearly.

Referring now to Figs. 1, 2 and 3, A indicates a crane arm, having at its lower end a toothed segment or sector α . As shown, a frame B is mounted on a mast or pedestal C, the said frame being provided with a rack b at its lower end. The crane arm is preferably pivoted at d to swing vertically and such pivot is suitably guided as by the guide d' . The said crane arm is preferably pivoted to a nut or block (not shown) which is internally threaded to coact with and travel on the worm D in substantially the manner shown and described in my former

application, Ser. No. 450,605, filed on the 28th day of August, 1908.

Obviously when the worm is rotated in either direction the pivot d will be compelled to travel along the worm, carrying the arm A outward or inward according to the direction of rotation, and the segment α will be forced to roll along the rack b . During such movement of the arm A, it will also be caused to swing vertically on the pivot d .

The frame B is pivoted on the mast or pedestal C, which acts as a vertical pivot to permit the frame and with it the crane and other parts to be rotated thereon. I preferably employ ball bearings e , e' or other suitable anti-friction devices in hubs or collars E, E' and bearing between the same and the mast or pedestal C.

Extending rearwardly from the collar E is a bracket B' which supports an operating shaft H journaled in suitable bearings h at one end, its other end being reduced and bearing in a bearing provided therefor in the worm shaft D. Loosely mounted on the operating shaft H is a vertical bevel-pinion F engaging with a bevel-gear wheel G fixed to the mast or pedestal C above the hub or collar E. The inner face of the bevel-pinion F is provided with a counterpart box I having the usual projections and interdental spaces. The rear end of the worm shaft D terminates at the rear of the bearing d in a similar counterpart box D² also having the usual projections and interdental spaces. Intermediate the counterpart boxes I and D² and slidingly secured to the shaft H in any suitable manner is a double clutch or clutch box J, the side or coupling faces of which are provided with projections and interdental spaces corresponding to those of the boxes I and D² and adapted to coact therewith.

A lever K pivoted at k to a bridge piece L is adapted to shift the clutch or clutch box J into engagement with either counterpart box as desired. A locking rod K' cooperating with notches k' in the bridge piece L and lever K serves to lock the clutch box J into engagement with either of the counterpart boxes or in its neutral position, as shown. The rod K' is provided with a hand lever k^2 adapted upon manipulation to withdraw the locking rod K' to permit the lever to be moved. A crank-wheel M is fixed to the operating shaft H.

A rope drum N is secured to a shaft n suitably supported in the frame B, which shaft is operated as shown by the crank-wheel N' and gears N², N³. The rope drum N projects at one side of the frame B and carries a rope N⁴ running over a pulley P and having at its free end a hook Q or other suitable securing device.

The operation of the device is as follows:

10 When it is desired to pick up an object at a distant point and move it to another point, the lever is operated to shift the clutch J into engagement with the counterpart box on the rear end of the worm shaft D, and

15 the crank-wheel M is rotated to swing the crane arm outwardly. The rope on the rope drum is then given out and its end secured to the load to be moved. The rope may then be wound on the drum to lift the load the necessary distance for horizontal swinging or in some instances the mere vertical swinging of the crane arm on its pivot d caused by the rotation of the crank wheel in the reverse direction will be sufficient for this purpose.

20 If the point to which it is desired to move the load is to either side or to the rear of the crane arm, the lever K is operated to move the clutch out of engagement with the counterpart box on the worm shaft D and

25 into engagement with the counterpart box on the pinion F, and the crank wheel M is operated to swing the crane horizontally to such desired point, the pitch of the thread of the worm being sufficient to hold the

30 crane arm at any desired position. When such desired point is reached the clutch may be again shifted into engagement with the counterpart box on the worm shaft and the crank-wheel M operated to lower the load

35 by swinging the crane arm vertically, and lowering away on the rope as may be found necessary or expedient. The load is then released from the rope and such operations continued as required.

40 Referring now to Figs. 4 and 5, 1 is a crane arm having at its lower end a toothed segment 2. 3 is a frame mounted as shown to swing horizontally on the balls 5 and rollers 6, operating respectively on the post

45 7 and base plate 4, the post 7 acting as a vertical pivot about which the base plate and frame turn. A worm 8 is supported in said frame 3 to have rotary but not longitudinal movement, which worm extends

50 through a threaded nut 9 which is slidably supported on the rod 10 also mounted in the frame, and the crane arm is pivoted to the nut 9 as indicated at 11. The crane arm, as shown, is curved forwardly and the

55 pivotal connection is at what I shall term the front side thereof, and it will be observed that with the pivot 11 as a center, the radii of the segment gradually increases from the rear end to its front end. Said

60 segment is preferably provided with a central

track and two sets of teeth which coöperate with a rack rigidly supported in the lower end of the frame, as more particularly described in said former application, Ser. No. 450,605. As shown the rack inclines downwardly from its rear to its front end and the post upon which the frame swings horizontally is located centrally beneath said rack. A crank handle 12 and gears 13 and 14 are provided to rotate the worm which will cause the crane arm to swing vertically as heretofore described. A rope drum 15 is journaled on a shaft 16 suitably supported in a bracket 17 secured on the plate 4. Any suitable mechanism, such as crank-handle 23 and gears 21 and 22 may be provided for the operation of the rope drum 15. The rope drum carries a rope 18 running over the pulley 19 and provided at its free end with an attaching device 20. The operation of this device is substantially the same as that illustrated in Figs. 1, 2 and 3. A lever X, shown as partially broken away, may be employed to swing the frame horizontally, or mechanism similar to that shown in Figs. 1, 2 and 3 may be employed, so that the horizontal swinging may be accomplished by the same shaft and crank which actuates the rope drum or the vertical swinging of the crane.

I claim:

1. In a crane or derrick, a frame adapted to rotate about a vertical pivot, a crane arm having a segment at its lower end supported in said frame, a horizontal pivot about which the crane arm may turn in a vertical plane, and a rack supported in said frame on which said segment may roll, substantially as described.

2. In a crane or derrick, a horizontally swinging frame, a crane arm supported in said frame to swing vertically and provided at its lower end with a segment, a rack supported in said frame on which the segment may roll, a rope drum supported in said frame, means for swinging the frame horizontally, means for swinging the crane arm vertically, and means for operating the rope drum.

3. In a crane or derrick, a frame adapted to rotate about a fixed vertical pivot, a crane arm having a segment at its lower end supported in said frame, a pivot about which the crane arm may turn in a vertical plane, and a rack supported in said frame on which said segment may roll, substantially as described.

4. In a crane or derrick, a frame adapted to rotate about a vertical pivot, a crane arm having a segment at its lower end supported in said frame, a horizontal pivot about which the crane arm may turn in a vertical plane, a rack supported in said frame on which said segment may roll, and interchangeable actuating means adapted to

swing the crane arm or frame alternately, substantially as described.

5. In a crane or derrick, a frame adapted to rotate about a vertical pivot, a crane arm supported in said frame and provided at its lower end with a segment having its radii gradually increasing from its rear to its front end, a horizontal pivot about which the crane arm may turn in a vertical plane, and 10 a rack supported in said frame and inclining downwardly from its rear to its front end.

6. In a crane or derrick, a frame adapted to rotate about a vertical pivot, a crane arm having a curved surface at its lower end supported to swing vertically in said frame; a base supported by said frame on which said curved surface rolls, means for preventing said curved surface from slipping on said base, means for swinging the frame horizontally and means for swinging the crane arm vertically.

7. In a crane arm or derrick, a frame adapted to rotate about a fixed vertical pivot, a crane arm having a curved surface

at its lower end supported to swing vertically in said frame, a base in said frame on which said curved surface rolls, means for preventing said curved surface from slipping on said base, a worm shaft for swinging said crane arm vertically journaled in the frame and having a counterpart clutch-box at its rear end; a pinion fast on said vertical pivot, an operating shaft journaled in the frame to rotate independently of said worm shaft, a pinion loosely mounted on said shaft, meshing with the pinion fast on the vertical pivot and having a counterpart box, a clutch-box intermediate said counterpart boxes and means for shifting the same alternately into engagement therewith.

In witness whereof, I have signed my name to the foregoing specification in the presence of two subscribing witnesses.

ANDREAS P. LUNDIN.
